HEEL-LIFT-CEMENTING MACHINE

Application filed March 30, 1927. Serial No. 179,639.

This invention relates to machines for cementing boot and shoe parts and is illustrated as embodied in a machine designed for applying latex to the faces of heel lifts.

In building heels of leather or leather-board, cement has very commonly been applied to the heel lifts to perfect a close bonding of the various lifts in the completed heel. The cement most commonly used is a paste which must be still moist for the heel-building operation. As a result, the application of cement or adhesive to the lifts of heels has usually been made an incident to the assembling operation, performed so shortly before the heel-building that there will be no opportunity for the paste to dry out before the lifts are brought together. It has been found, however, as set forth in Letters Patent of the United States No. 1,779,368 granted Oct. 21, 1930, upon an application of James Cavanaugh, Serial No. 62,487, filed Oct. 14, 1925, that the peculiar properties of latex render it particularly adaptable to cementing the opposed faces of the lifts of heels, since it may be applied to the lifts whenever, prior to the building of the heels, it is most convenient to do so. Thus latex may be applied to the opposed faces of each of the heel lifts at any convenient time and allowed to dry, after which the lifts may be put aside for a greater or less period prior to the building of the heel with the assurance that the cementitious coating upon the lifts will be in condition to join them together under the pressure of the heel-building machine even though a very considerable period may have elapsed between the time of the application of the latex and the building of the heel. Furthermore, the distortion which accompanies the compressing operation does not result in lessening the adhesion of latex-coated lifts.

An object of the present invention is to provide an improved machine for the application of cements including latex to the opposed faces of boot and shoe parts, such as

heel lifts, by means of which the work may be done quickly and neatly without wasting the latex, if that be used, or causing it to coagulate in the machine, and with the assurance that the coating will be thoroughly and evenly applied.

The illustrated machine is provided with adjacent horizontally-disposed applying rolls having substantially parallel axes and having their adjacent faces arranged to coact with the opposed faces of heel lifts. For convenience in handling the lifts and in delivering the latex to the opposed sides of the lift, the axes of these rolls are preferably arranged in a horizontal plane so that the work passes vertically between the rolls and may be received for removal in any desired fashion such as by an endless conveyor placed beneath the machine.

In order to facilitate the handling of the lifts which are delivered to the machine in bulk, a sorting table is preferably provided above the machine, and, in accordance with a feature of the invention, the illustrated table is made of reticulated material, in order to allow some of the dirt which accompanies the lifts to drop through the bottom of the table, and is provided with an upstanding rim around an inlet opening for delivering the lifts directly to the applying rolls of the machine, said rim facilitating the exclusion of the dirt which accumulates in the neighborhood thereof and preventing it from being brushed into the opening and thus on to the rolls.

Another feature of the invention resides in the construction and arrangement of a guide chute associated with the inlet opening whereby the correct delivery of lifts through the chute is assured. The illustrated guide chute is provided with inclined sides one of which is yieldable under the action of a spring sufficiently stiff to prevent more than one lift passing through the guide chute at a time but sufficiently flexible to prevent

breakage, in case the lift being pulled through the opening by the action of the applying rolls has a portion slightly thicker than the distance between the edges of the outlet opening of the guide chute. Preferably, adjustment is provided for the yielding face of the chute so that the size of the outlet opening may be adjustably determined in accordance with the average thickness of the lifts being presented.

In utilizing the machine for the application of latex to wedge lifts, it is necessary to present these lifts to the applying rolls axially with either their thinnest edge or thickest edge toward the rolls so that the rolls will bear evenly upon the whole width of the lift.

Accordingly, one end face of the illustrated chute is made adjustable to vary the length of the chute, to equal the width of the wedge lifts so that they must be presented axially and the adjustable face just referred to has an overhanging cover which closes the space between said face and the adjacent end of the chute opening, thus excluding dirt at this point. Further to facilitate this operation of coating wedge lifts, one of the illustrated applying rolls is yieldingly mounted, being spring-pressed toward the other roll and limited in its inward movement.

Because of the irregularities in the surfaces of shoe parts, such as heel lifts, it is found desirable to provide a yielding surface upon each of the applying rolls. In addition to this and because of the variation in the thickness of different sets of lifts, provision is also made, in accordance with another feature of the invention, for mounting one of the illustrated applying rolls for adjustment toward the other roll.

In order that the quantity of latex applied to the work may be controlled readily without coagulation, the illustrated machine is provided with doctor or scraper rolls which are turned in the same direction of rotation as the applying rolls but with a much smaller peripheral speed, and provision is made for mounting one of these rolls upon the support which carries the adjustable applying roll and for maintaining it in adjusted relation to said roll.

Other features of the invention reside in work-stripers removably mounted upon the edges of a latex receptacle below the applying rolls for preventing the pieces of work from adhering to said rolls and in a construction by means of which latex picked up by said strippers may be carried back into the latex receptacle.

Still another feature of the invention resides in the provision of an inclined work-guiding or diverting member beneath the delivery opening of the machine. This member is arranged to guide the work with as little disturbance of its coating as possible

to a receiving device, such as an endless conveyor, and to take care of the drippings of the cement from the work or from the machine and dispose of said drippings by diverting them beyond the bounds of the receiving device.

These and other features of the invention will now be described with reference to the accompanying drawings in which:

Fig. 1 is a side elevation of a preferred embodiment of the invention with parts broken away and in section;

Fig. 2 is a horizontal section with parts broken away;

Fig. 3 is a fragmentary perspective of a portion of the sorting table and the guide chute;

Fig. 4 is a detail section of the diverting member upon the line IV—IV of Fig. 1, and

Fig. 5 is a fragmentary perspective showing the work strippers.

The illustrated machine embodies a pair of rotary applying rolls 10 and 12 journaled side by side upon substantially parallel, horizontal axes within a supporting casing 14, the roll 12 being supported upon a shaft 16 directly journaled in bosses 18 formed upon the sides of the casing. Each of the rolls may be made up of a hollow cylindrical metallic roll 20 provided with a yielding applying surface 22 which preferably is somewhat yielding in order that the surfaces of the rolls may conform to slight irregularities or wrinkles in the surfaces of the pieces of work. The surface 22 may be made of a gelatinous compound, similar to that used on the ink rolls of printing presses, which is unaffected by the latex used and is readily cleanable. In addition to this provision of a yielding surface upon each of the rolls, the applying roll 10 is carried upon a shaft 24 which is journaled between the sides of a hanger 26 supported upon a pivot rod 28 carried by bosses 30 upon the casing 14. This hanger 26 with the roll 10 is resiliently urged toward the other roll 12 by means of a spring 32 surrounding a rod 34 which is pivotally attached at one end to said hanger and at its other end passes through a boss 36 in the casing through which its movement is limited by means of an adjustable stop nut 38. This nut is disposed in a convenient position upon the outside of the casing 14.

The supply of coating material, such as latex, is carried in receptacles 40 and 42 shown as formed integrally with the casing 14 and having separate inclined edges 44 and 46 which are separated to provide a delivery opening 48 through which treated pieces of work may drop. To facilitate the maintenance of a proper quantity of liquid in these receptacles, a barometric supply device is provided comprising hollow brackets 50 secured by thumb screws 51 to the casing 14 to communicate with the receptacles and arranged

to support in inverted position supply bottles 52 which rest upon rubber washers 54 and are held in upright position against curved vertical flanges 56 by detachable spring loops. The distance of the ends of the bottle necks from the bottoms of the receptacles is determined by posts 58 so that the supply of liquid is maintained substantially at the level determined by the outlet opening of the bottles and at a point slightly below the edges of the inclined ends 44 and 46 of receptacles adjacent to the delivery opening 48. This barometric action is facilitated by the tight joint between the bottles 52 and the brackets 50 provided by the rubber washers 54.

Devices of one sort or another called "doctors" are commonly employed in cementing machines for regulating the quantity of material upon the surfaces of the applying rolls. In using latex in such machines, it has been found that a doctor in the form of a scraper bar is ill adapted because any frictional action between the scraper and the latex sets up a coagulation which forms ball-like masses of rubber which bear against the surface of the applying roll and remove material therefrom in streaks. On the other hand, a rotary doctor or scraper roll turning in the opposite direction of rotation from the applying roll, so that adjacent surfaces are moving in the same direction (whether turned by frictional contact with the applying roll or driven positively in that direction) causes a squeezing of the latex between the two rolls and sets up coagulation in much the same fashion that the friction of a scraper bar does. It has been found, however, that if the rotary doctor roll is positively driven in the same direction of rotation as the applying roll, and preferably at a much less peripheral speed, its control of the quantity of latex is unattended by any detrimental coagulation. The action of such a rotary doctor roll may be determined by controlling accurately the spacing between the doctor roll and the applying roll.

Accordingly, a doctor roll 60 is provided for the applying roll 12, the roll 60 being supported in hangers 62 carried upon a transverse rod 64 extending between the sides of the casing and being driven by means of a chain 66 surrounding sprockets upon the shaft 16 of the applying roll and the shaft 68 of the doctor roll, respectively. A suitable slot is provided in one side of the casing 14 to allow adjustment of the position of the shaft 68 of the doctor roll, and this adjustment is determined by means of a turnbuckle 70 co-acting with rods 72 extending to the shafts 16 and 68, respectively. A doctor roll 76 for the applying roll 10, on the other hand, is supported in hangers 78 pivoted upon arms 80 extending out from and forming a part of the hangers 26 in which the roll 10 is supported. Similarly to the doctor roll 60, the roll 76 is driven by a chain 82 passing over sprockets

on the shaft 24 of the applying roll and the shaft 84 of the doctor roll 76. The shaft 84 of the doctor roll 76 is held rigidly at the desired distance from that of the applying roll by means of a rod and turnbuckle connection 86. As a result of this construction, adjustment of the position of the applying roll 10 does not affect the relation between said applying roll and its doctor roll 76. At the same time an adjustment of the relation between the two latter rolls may be effected by adjusting the turnbuckle connection 86. Thus each set of co-acting applying and doctor rolls are rotated in the same direction and the size of the sprockets is such that the peripheral speed of the doctor rolls is considerably less than the peripheral speed of the applying rolls.

The machine may be supported upon legs 90 and 92, the latter of which is provided with a shelf 94 for the support of the driving motor 96. A pinion 98 on the motor shaft meshes with a gear 100 which, fixed to another speed reducing gear 102, is freely rotatable upon a stub shaft 104 carried in the casing of the machine. Gear 102 meshes with gear 106 secured to the shaft 16 of the applying roll 12 and similar gears 108 and 110 are provided to interconnect the shafts 16 and 24 of the applying rolls, said gears being made with sufficiently deep teeth so that the driving connection is substantially unaffected by the adjustment of the position of the applying roll 10. A casing 112 may be provided to cover the driving gears, and covers 114 (Fig. 1) are mounted upon the opposite face of the casing 14 over the chains 66 and 82. Hinged covers 116 pivoted along the upper edges of the casing 14 are provided to exclude dirt from the interior of the machine while allowing access thereto for adjustments or cleaning.

As the heel lifts, for example, are delivered in bulk to the machine, they are spread out upon a sorting table 120 and are passed manually by the operator through an inlet opening leading to a guide chute 122 which delivers the lifts to the meeting point of the applying rolls. After the application of latex to both sides of the lifts, they are discharged through the delivery opening 48 where they fall upon an inclined diverting member or trough 124 supported as shown in Fig. 1 and slide off to the surface of a conveyor belt 126 which is arranged to support the lifts for a sufficient length of time or to carry them through a drying apparatus to allow the water mixed with the latex to be dried out so that the lifts may be handled.

The sorting table 120 is provided with reticulated sides 128 and bottom 129 carried upon a framework 130 which is supported by means of brackets 132 (Fig. 1) bolted to the casing 14 of the machine. This allows the lifts to be spread out in convenient position

for the operator and at the same time permits dust and dirt which may have collected with the lifts to pass through the reticulated bottom 129 of the sorting table. This sorting table is joined adjacent to its central portion to a cover member 136 (Fig. 3) provided with an upstanding rim 138 surrounding an inlet opening communicating with the guide chute 122, a part of which is formed as a part of the casting of the casing 14 of the machine. This rim 138 facilitates the exclusion of dirt from the guide chute when the machine is being operated or when the dirt is being brushed out of the sorting table.

The guide chute is constructed with vertical, tapered end members 140 joined to inclined side members 142 which are tapered at their lower edges, and one portion 144 of one of these side members is secured to a rod 146 extending through and pivoted in the outer sides of the casing 14. The position of this pivoted side 144, which is located between the end members 140, may be determined by means of an arm 148 connected to a rod 150 passing through a boss 152 upon the casing. An adjustable stop screw 154 limits the upward movement of the rod 150 under the action of a spring 155 surrounding said rod, said spring being sufficiently stiff normally to prevent more than a single lift from passing through the outlet of the guide chute and sufficiently resilient to permit the side 144 to be pushed aside slightly in case a lift, such as a wedge lift, having a part thicker than the width of the outlet opening has passed partly therethrough and been seized by the applying rolls, thus preventing breakage of the machine.

In handling lifts of substantially uniform thickness, it is not material whether the rounded end or the heel-breast end of the lift is passed first through the rolls, or, indeed, whether these lifts are passed through sidewise or endwise. On the other hand, because a transverse cross-section in any direction is substantially rectangular, when the operator is dealing with wedge lifts where a cross-section from front to back, or in any direction except at right angles to its longitudinal axis, is inherently tapered, it is important that they be passed through the rolls with either the thinnest or the thickest edge foremost so that the cross-section of the part with which the cement applying rolls are contacting at any one time is substantially rectangular. This insures a firm contact and an even coating of latex. This operation is facilitated by the provision in the guide chute of an adjustable end piece 156 of a triangular shape, the position of which between the inclined sides 142 and 144 may be determined by a screw 158 extending through the casing 14 and operated by a knurled finger piece 160 secured to the outer end of the screw. Associated with this triangular piece 156 is an ex-

tension 162 of thin metal, the upper end 164 of which is bent over horizontally to cover part of the inlet opening defined by the upstanding rim 138, thus excluding the dirt from the unused portion of the inlet opening and preventing the accidental insertion of pieces of work therein. By adjusting the position of the triangular end piece 156, its distance from the further end 140 of the guide chute 122 may be set to be equal to the transverse width of a wedge-shaped lift which dimension usually, if not invariably, will be less than the length thereof. Consequently, such wedge lifts may only be passed through the guide chute lengthwise with their thinnest or thickest edges foremost in the direction of the longitudinal axis of each lift and may not be passed through sidewise.

While a large part of the pieces of work drop freely away from the applying rolls through the outlet 48, it sometimes happens that pieces will stick to one or the other of the applying rolls and attempt to follow around into the receptacles. To prevent such action, strippers 170 are provided each comprising a plate upon the upper surface of which are provided ribs or fingers 172 (Figs. 1 and 5) having sharpened ends 174 which are brought into close relation to the applying rolls to rake off any pieces of work which may be clinging to said rolls. These stripper plates 170 are supported in inclined position above the inclined edges 44 and 46 of the receptacles by means of suitably formed lugs 176 whereby the stripper plates 170 may be slipped over the edges of said receptacles or removed therefrom for cleaning. Adjustment of the position of the roll 10 away from the corresponding stripper plate 170 does not destroy the effectiveness of the latter because the machine is then used for thicker lifts which cannot pass between the roll and the stripper. It should be noted that the inclined plates 170 of the work strippers are so supported with respect to the edges 44 or 46 of the receptacles that any drippings passing over either the upper or lower surface of said plates (see Fig. 1) will be carried back into the receptacles instead of being allowed to pass out through the opening 48.

In spite of this provision, there are occasional drippings from the co-acting surfaces of the applying rolls and sometimes the pieces of work have an excess of coating material which promptly drops off on the diverting trough 124. For this reason, said diverting member is made of corrugated material having ribs 180 and intermediate grooves 182. When a heel lift, such as that shown at 184, slides over the surface of the diverting member, it rests upon the ribs 180. Since any drippings which may have been deposited upon said member are carried into the grooves 182, the removal of an excess of

material from the lifts 184 is prevented and said lifts are not required to pass over coagulated drippings or possible dirt which may have collected on the diverting member.

5 In case the quantity of drippings is sufficient so that it runs down the grooves 182, a gutter 186 is provided at the bottom of said diverting member 124 extending transversely thereof for diverting said drippings laterally to a suitable receptacle out of range of the conveyor belt 126. The diverting trough 186 is of somewhat less depth than its associated corrugated diverting member 124, as shown in Fig. 4, allowing the lifts to pass by the 10 end of the diverting member without being scraped thereby.

15 Lips 188 (Figs. 1 and 5) have been provided on the inclined edges 44 and 46 of the receptacles 40 and 42 so that any latex accidentally spilled over said edges will drop off 20 on to the diverting member 124 rather than running down the bottoms of the receptacles.

When it is desired to empty either of the receptacles 40 or 42, a pan may be placed 25 upon a corresponding shelf 190 or 192 upon the legs 90 and 92 as the bracket 50 is removed to drain the receptacle. A lip 194 beneath the opening in the exterior wall of the receptacle carries the latex into the pan 30 rather than allowing it to run down the legs.

Having described the invention, what we claim as new and desire to secure by Letters Patent of the United States is:

35 1. In a machine for applying cement to the opposed faces of boot and shoe parts, an applying roll, means for supplying cement thereto, means for controlling the amount of cement supplied to said roll, an opposed applying roll, a hanger supporting said roll, means for controlling said hanger to control the relation of the adjacent faces of the applying rolls, means for supplying cement to the second applying roll, and driven means 40 rotatable in a definite relation to said second applying roll for controlling the amount of cement applied by said latter roll.

50 2. In a machine for applying cement to the opposed faces of boot and shoe parts, a plurality of co-operating applying rolls, means for supplying cement to each of said rolls, a continuously rotatable doctor roll controlling the cement on one of said rolls, means for supporting one of said rolls comprising a pivoted hanger having bearings for said doctor roll, resilient means urging said hanger in one direction to bring the applying rolls 55 toward each other, and means for limiting the movement of said hanger toward the other roll.

60 3. In a machine for applying cement to the opposed faces of boot and shoe parts, a plurality of applying rolls, means for supplying cement to each of said rolls, means for supporting one of said rolls for adjustment

toward and away from the other roll comprising a pivoted hanger, a rotary doctor roll also supported upon said hanger, means for driving said doctor roll to control the amount of cement supplied to the related applying roll, and means for adjustably fixing the 70 position of the doctor roll with respect to the applying roll.

4. In a machine for applying cement to the opposed faces of boot and shoe parts, a plurality of applying rolls, means for supplying cement to said rolls, a support for one of said rolls movable toward and away from the other roll to allow the relation of said roll with respect to the other roll to be varied, 75 means for controlling the position of said movable support, a rotary doctor roll also carried by said movable support and arranged to be driven from its related applying roll, and means for determining the approach of 80 the doctor roll to the applying roll.

5. In a machine for applying cement to the opposed faces of boot and shoe parts, a pair of applying rolls disposed side by side with both axes in a substantially horizontal plane 90 to provide an up and down passage for boot and shoe parts passed downwardly between said rolls, an inclined diverting trough disposed beneath the opening between said rolls, said trough being provided with a plurality of closely spaced ribs to support successive pieces of work as they travel in a downward path, and means for receiving and diverting laterally of the path of travel of the work pieces any excess cement which may be deposited upon said inclined diverting member 95 between the ribs thereof.

6. In a machine for cementing the opposed faces of boot and shoe parts, co-operating applying rolls disposed side by side, cement-supplying receptacles beneath said rolls arranged with their adjacent edges in spaced relation to provide a vertical passage for pieces of work coated by the adjacent faces of said applying rolls, a work diverting trough 100 inclined downwardly beneath the opening between said rolls and said receptacles and made of corrugated material having closely spaced ribs supporting pieces of work traveling down said diverting trough, and a gutter arranged transversely of said member beneath the lower ends of the grooves of said corrugated material but out of contact with the pieces of work, whereby the pieces of work 105 may slide over the ribs of the corrugated member and the gutter and any surplus cement which may drop off from the pieces of work or from the applying rolls will be collected in the grooves of the corrugated trough and carried to one side by this co- 110

operating gutter.

7. In a machine for coating the opposed faces of boot and shoe parts, a pair of applying rolls arranged horizontally opposite one another, cement-supplying receptacles dis- 115

posed beneath said rolls having their adjacent edges spaced apart to provide a passage for boot and shoe parts which are presented to and passed downwardly between said applying rolls, and work-stripping devices co-operating with said applying rolls beneath their horizontal axes and arranged to carry into the cement-supplying receptacles drippings of cement collected by the stripping devices.

8. In a machine for cementing boot and shoe parts, an applying roll, a receptacle for supplying cement to the roll disposed therebeneath, and a stripper-plate arranged to prevent shoe parts presented to the applying roll from entering the receptacle, said stripper-plate being arranged in an inclined position beneath said roll with one of its edges overhanging the edge of the cement-supplying receptacle so that cement collected thereby will drip back into the receptacle.

9. In a machine for cementing boot and shoe parts, a supply receptacle, an applying roll overhanging the edge of the receptacle, a stripper-plate mounted on the edge of the receptacle arranged to prevent the passage into the receptacle of shoe parts presented to the applying roll, said stripper-plate having upper and lower surfaces arranged in inclined positions and so disposed with relation to the edge of the receptacle that cement collecting upon either surface will drip back into the receptacle.

10. In a machine for cementing boot and shoe parts, a supply receptacle having an inclined edge, an applying roll overhanging the edge of said receptacle, and a stripper-plate arranged to prevent the passage into the receptacle of shoe parts presented to the applying roll, said stripper-plate being supported in an inclined position upon the edge of the receptacle with its lower face spaced from the edge of the receptacle and overhanging said edge.

11. In a machine for cementing boot and shoe parts, an applying roll having a side exposed and arranged to apply cement to work presented to the side of the roll at a point approximately horizontally opposite its axis and moved in an upright path alongside said roll, a receptacle for supplying cement to the roll disposed therebeneath having one edge out of the upright line of movement of the piece of work presented as above recited, and a work-stripping device co-operating with said applying roll supported in close relation with the surface of the roll to underlie the roll beneath the point of application of the work thereto constructed and arranged to strip off pieces of work adhering to the roll without removing cement from the roll.

12. In a machine for applying cement to the opposed faces of boot and shoe parts, a pair of applying rolls disposed side by side

upon substantially parallel horizontal axes, a separate cement receptacle disposed beneath each of said rolls, said receptacles having their adjacent edges sloped inwardly and upwardly toward the adjacent faces of the rolls but spaced apart from one another and from the path of boot and shoe parts passing vertically between and in contact with the rolls, and a work-stripping device removably mounted upon said edge of one of said receptacles for raking off pieces of work accidentally adhering to one of the rolls.

13. In a machine for applying cement to the opposed faces of boot and shoe parts, a pair of applying rolls disposed side by side upon substantially parallel horizontal axes, cement receptacles disposed beneath said rolls having their adjacent edges spaced apart from one another and from the path of boot and shoe parts passing vertically between the rolls, and a work-stripping device mounted upon said edge of one of said receptacles, said device comprising a plate provided with spaced members in juxtaposition to the roll to strip work therefrom, said plate being supported with its lower edge above the receptacle, whereby drippings from said plate are carried back into the receptacle.

14. A machine for cementing the opposed faces of boot and shoe heel lifts comprising a cementing machine embodying a pair of horizontally disposed applying rolls arranged side by side, a sorting table arranged above said applying rolls, said table having an inlet opening in said sorting table above the meeting point of said rolls through which lifts can be dropped, and an upstanding rim around said opening to prevent refuse from being brushed into the space between the applying rolls.

15. In a machine for cementing heel lifts, a cement-applying device having a work receiving package arranged for the vertical passage of lifts therethrough and provided with a cover, a sorting table supported above said machine and provided with a reticulated bottom portion, said table having an inlet opening over the work receiving passage and through said sorting table surrounded by an upstanding rim to prevent the admission of refuse which may be collected from the heel lifts.

16. In a machine for cementing heel lifts, a cement-applying device arranged for the vertical feeding and passage of the lifts therethrough, a guide chute for guiding the heel lifts in determinate positions to said applying device, said chute having inclined sides, means for adjusting the relative position of said sides to control the size of the outlet opening of said chute, and means for resiliently holding one side in adjusted position.

17. In a machine for cementing boot and shoe parts, a cement-applying device ar-

5 ranged for the vertical feeding and passage of work therethrough, and a guide chute at the top of the machine for guiding pieces of work in determinate positions to said applying device, said chute having inclined sides and parallel ends, one of which ends is adjustable to control the size of the chute.

10 18. In a machine for cementing boot and shoe parts, a cement-applying device arranged for the vertical feeding and passage of work therethrough, and a guide chute at the top of the machine for guiding pieces of work in determinate positions to said applying device, said chute having an adjustable 15 end member provided with an overhanging cover portion movable therewith and arranged to cover the space between said end member and the end of the chute.

20 19. In a machine for cementing boot and shoe parts, a cement-applying device arranged for the vertical feeding and passage of work therethrough, a guide chute for guiding pieces of work in determinate positions to said applying device, said chute having a side which is resiliently held in position, and an adjustable end piece co-operating therewith to control the size of the chute.

25 20. In a cement-applying machine, a casting providing a cement receptacle and having an opening in its exterior wall, a supply member arranged to be detachably secured to said exterior wall in communication with said opening, and an outwardly projecting lip positioned below the opening in said exterior wall arranged to divert cement flowing out of the opening when the supply member is removed.

30 21. In a machine for cementing boot and shoe parts, cement receptacles, horizontally opposed applying rolls journaled above and overhanging said receptacles, and work-stripping devices removably secured to adjacent edges of the receptacles and adapted to detach pieces of work adhering to the 35 rolls without removing cement from the rolls.

40 22. In a cementing machine for boot and shoe parts, a cement-applying device comprising horizontally opposed rolls, and a guide chute above and symmetrically placed with respect to said rolls, said chute being constructed and arranged resiliently to grip pieces of work presented thereto and depending from the chute until they are pulled 45 out by the rolls.

50 23. In a machine for cementing heel lifts, horizontally opposed cement-applying rolls, and a guide chute above said rolls, said chute extending into close proximity to the 55 bite of the rolls and dimensioned to correspond to single pieces of work thereby to direct lifts in determinate positions until engaged by the rolls.

60 24. In a machine for cementing wedge heel lifts, rotatable cement-applying rolls,

one of said rolls being resiliently pressed toward the other, and a guide chute before the rolls having sides constructed and arranged to direct wedge lifts to the rolls with each lift moving in the direction of its longitudinal axis.

70 In testimony whereof we have signed our names to this specification.

FRED ASHWORTH.
